TIE PLATE RAIL ANCHORS

James R. Steele and Stephen M. Lounsherry, Jr., Owego, N. Y., assignors to Moore & Steele Corporation, Owego, N. Y., a corporation of Delaware

Application February 3, 1955, Serial No. 435,934

22 Claims. (Cl. 238—327)

This invention relates to anti-creep devices for railroad rails, and more particularly to a rail anchor adapted to be applied to a rail and which will bear only against the adjacent tie plate, having no direct engagement with the tie itself. This application is a continuation-in-part of our application Serial No. 431,906, filed May 24, 1954, and now abandoned.

Conventional rail anchors which resist creeping of the rail by bearing against the tie, or by bearing against both the tie plate and tie, do not distribute the creeping load equally and uniformly to the ties. The reason for this is because of the variation in the hardness and density of the different ties in the track structure as well as the differences in the character of the surfaces the ties present to the abutting anchor.

A rail anchor that bears against the tie plate only is advantageous because the creeping load is applied directly to the tie plate which in turn carries this load directly to the spikes which are in firm engagement with the tie. The creeping loads imposed in a stretch of track, equipped with anchors that bear against the tie plate, will be transmitted evenly to all anchors in the stretch because each anchor will be in contact with a solid abutting surface.

There have been attempts, heretofore, to provide rail anchors which were made to bear against the tie plate, but they were not commercially successful because such anchors were so designed that they could not be made, in a size that would be effective, at a price that would be competitive with conventional anchors.

The general object of the invention is to provide a rail anchor of the type described, of simple and economical construction, which can be produced at a sufficiently low cost to allow the anchor to be used on both sides of the tie plate, where necessary, for "two-way" anchorage of the rail.

The anchor of the present invention is made from a length of rolled stock, formed or supplemented in such a way that the cross-section of the stock, in the intermediate portion which is bent into substantial U-shape, is greater in its dimension transverse to the rail axis than are the respective end portions. Thus the section modulus of the intermediate portion is greater than would otherwise be the case with stock of the particular dimensions used. This may be accomplished by forming one or more bulges or ribs in the intermediate portion, by twisting the stock through 180° in the same portion, by forming edge flanges thereon, or by supplementing the original stock in the area in question by adding material.

More specifically, it is an object of the invention to provide a rail anchor of the type described, comprising a lower portion adapted to extend across the bottom of the rail base and having an upturned extremity bearing against an edge of the rail base, an upper portion extending at a vertical angle to the lower portion and adapted to rest upon the upper face of the said rail base on one side of the web of the rail, i. e. against the upper face

2

of one rail base flange, and a generally U-shaped intermediate portion joining the upper and lower portions, the intermediate portion being formed or supplemented to increase the section modulus thereof.

5 A further object is the provision of a rail anchor as described in the preceding paragraph, in which the said upper portion extends at a vertical angle to the lower portion, which angle is less than the corresponding angle between the upper and lower faces of the rail base, whereby the anchor, when applied to the rail, exerts a resilient frictional grip upon the rail, said upper portion having an upturned extremity the lower surface of which is curved to match the fillet connecting the adjacent rail base flange with the web of the rail, whereby the frictional hold of the anchor upon the rail is increased.

A further object is the provision of a rail anchor of the type defined in the preceding paragraphs, in which the intermediate portion is formed or supplemented in any of the ways hereinafter described.

Another object is the provision of a tie-plate rail anchor of the type described having means facilitating its removal from the rail when desired. A further object is the provision of an anchor having superior gripping action on the rail by virtue of having its upper portion relieved centrally so as to grip the rail base along its two edges rather than over its entire area.

Other and further objects, features and advantages will be apparent from the description which follows, read in connection with the accompanying drawings in which:

30 Figure 1 is a view showing a rail in transverse section and the corresponding tie portion, tie plate, anchor, and spikes in side elevation, the anchor being shown in a position of partial application;

35 Figure 2 is a view similar to Figure 1, but showing the anchor in its final position on the rail;

Figure 3 is an elevational view at 90° to Figures 1 and 2, and showing the anchor in position as in Figure 2;

40 Figure 4 is a sectional view of the anchor on line 4—4 of Figure 1;

Figure 5 is a diagram illustrating the distribution of forces exerted on the rail by the anchor;

Figure 6 is a view similar to Figure 2, illustrating a modification of the anchor;

45 Figure 7 is an elevational view at 90° to Figure 6;

Figures 8 and 9 are top and bottom views, respectively, corresponding to Figure 6;

Figure 10 is a side elevation of a further modification, Figure 11 being an end elevation thereof;

50 Figure 12 is a sectional view on line 12—12 of Figure 13, which is a sectional view on line 13—13 of Figure 12, both views illustrating a further modification;

Figures 14 and 16 are side elevations of further modifications, Figures 15 and 17 being end elevations of the respective modifications;

55 Figure 18 is a fragmentary plan view corresponding to Figure 16;

Figure 19 is a fragmentary side elevation of a still further modification;

60 Figure 20 is a sectional view on line 20—20 of Figure 19;

Figure 21 is a side elevational view of a further embodiment of the invention, installed on a rail;

Figures 22 and 23 are opposite end elevations of the anchor of Figure 21;

65 Figure 24 is a fragmentary plan view of the anchor of Figure 21;

Figures 25 and 26 are sectional views on lines 25—25 and 26—26, of Figure 21, respectively;

Figure 27 is a fragmentary side elevation of a further modification of the invention;

70 Figure 28 is a fragmentary plan view of the modification seen in Figure 27; and

Figure 29 is an end elevation of the modification of Figure 27.

In order to facilitate an understanding of the invention, reference is made to the embodiments thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

As will be readily understood, the rail anchor of the present invention, like rail anchors generally, is intended to be used in combination with the usual rail 10, tie plate 11, and wooden cross-tie 12. The rail 10 comprises the usual head portion 13, web 14 and base 15, the latter comprising, in turn, opposed flange portions 15a and 15b. The tie plate 11 may be secured to the cross-tie 12 by means of the usual spikes 16 or in any suitable fashion. The base flanges 15a and 15b taper upwardly from their outer edges toward the web 14, to which they are joined by curved fillets 17a and 17b.

The rail anchor of the present invention, as exemplified in Figures 1-5, inclusive, is designated generally by the numeral 20 and comprises a lower portion 21 having an upturned extremity 22, and upper portion 23 terminating in the curved extremity 24, and an intermediate portion 25, bent in a shape generally corresponding to the letter U integral with and joining the portions 21 and 23. The anchor 20 is formed from a piece of spring steel of rectangular section of a thickness not greater than that of the tie plate so that, when in position on the rail 10, the anchor 20 cannot engage the cross-tie 12, but any creep loads will be transmitted through direct engagement between the anchor 20 and the tie plate 11. Preferably, the width of the anchor, i. e. its dimension parallel to the axis of the rail, will approximate seven times the thickness of the material from which it is formed, for example, it may be formed of $\frac{1}{4}$ inch stock, and a suitable width is $1\frac{3}{4}$ inches.

The lower portion 21 of the anchor is of a length approximating the transverse dimension of the rail base, while the upper portion 23 is somewhat less than one-half as long, since it is intended to engage and bear against only the upper surface of the base flange 15a and the adjacent fillet 17a. Joining the aforesaid lower and upper portions 21 and 23, is a U-shaped intermediate portion 25 which is bent in such a fashion that the upper portion 23 of the anchor extends at a vertical angle to the lower portion 21 which angle is less than the taper of the upper surface of flange 15a. Thus, the anchor must be sprung into place, after which the rail base will be tightly gripped between the portions 21 and 23 of the anchor.

For the purpose of strengthening the intermediate portion 25, and for another purpose mentioned hereinafter, the intermediate portion is formed with an outwardly bulging rib 26 extending longitudinally thereof and tapering in height from the respective ends of the intermediate portion, where it joins the upper and lower portions respectively, to a point midway therebetween. The shape of the rib 26 may be seen, in transverse section, in Figure 4. In the course of producing the rib 26, which is formed before the stock is bent into a substantial U-shape as described, the overall width of the stock is diminished in the neighborhood of the rib so that the width of the intermediate portion 25 of the anchor diminishes gradually from its respective ends to its midpoint. This feature may best be seen in Figure 3.

To apply the anchor to the rail it is placed on the rail base 15 as shown in Figure 1, then it is driven by a maul or sledge hammer until it is in complete gripping engagement with the rail as shown in Figure 2. In taking this gripping position on the rail, it is necessary for the anchor 20 to spring open so that the angle between the portions 21 and 23 increases from that seen

in Figure 1 to that seen in Figure 2. When the anchor has been applied correctly the extremity 22 engages the edge of the base flange 15b and the anchor grips the rail with forces distributed approximately as seen in Figure 5.

When a creeping load is applied to the anchor 20 by the tie plate 11, it is applied against the lower portion 21 of the anchor. This produces a torque which attempts to rotate the anchor about an axis X—X which is above the rail base 15 and which passes near or through the point A in Figure 2. This, in turn, causes the anchor to increase its grip on the rail, since the tendency to rotate about axis X—X is resisted by the resilient force tending to maintain portions 21 and 23 in their predetermined angular relationship. This tendency to rotate also brings the extremity 22 of the anchor into contact with the shoulder 11a of the tie plate 11, which in turn causes a tendency to rotate the anchor about an axis perpendicular to the rail base, thus causing the anchor to increase its grip on the rail, between the extremity 22 and the extremity 24. Due to the diminished width of the curved intermediate portion 25 of the anchor, the latter does not contact the adjacent shoulder 11b of the tie plate, which would counteract the effect just described.

The rail anchor of the present invention is effective and practical because of the following features, which are novel as applied to rail anchors of the present type.

(1) The longitudinal rib around the curved portion of the anchor increases the strength through this section, by increasing the section modulus in this portion, which is subject to the greatest deformation when the anchor is applied to the rail. Because of this rib it requires more force to open the anchor a certain amount than would be the case if the rib were not present. Therefore with this rib a smaller width and hence a lighter section of bar can be used to fabricate the anchor and, since the greatest cost in the manufacture of an anchor is the steel cost, it becomes possible, with the present design, to make an effective anchor which can be sold at substantially less than current conventional anchors.

(2) The method of take-up of the present anchor places the maximum amount of material in the anchor under stress so that it is used for gripping the rail.

(3) Due to the fact that the upper portion of the anchor extends into and bears against the fillet connecting the web and base of rail, there is no danger of over-driving this anchor when it is applied to the rail.

(4) The radius of the curved portion is made as large as possible in order to reduce the concentrated stresses in this section where stresses reach a maximum.

(5) The anchor bears against the tie plate only, thereby transmitting creeping loads to the tie through the spikes, which are already in close engagement with the tie. This insures that every anchor will transmit its load to the tie in exactly the same way as every other anchor, which will result in a uniform loading of ties in the stretches of track where this anchor is used out-of-face.

(6) The holding power of the anchor is effective from the moment of application.

(7) The anchor can be made inexpensively enough so that two anchors per tie may be used for two-way anchorage either out-of-face or spotted in where conditions require it.

(8) The present anchor eliminates the sawing action on the tie that occurs with a conventional rail anchor.

(9) It will not cause damage to the rail in the case of dragging equipment or a derailment because the raised rib supported by the wide bearing surface will cushion any blows received on the top of the anchor.

(10) It is highly improbable that the wheel treads could strike this anchor, in case of derailment, because they would be lifted over the anchor by the wheel flanges riding over the tie plate.

(11) No special tool is required.

(12) Low installation cost since the anchor is applied with a maul.

The rail anchor illustrated in Figures 6-9, inclusive, is similar to that of Figures 1-5, inclusive, except that the U-shaped intermediate portion 30 is formed by twisting the stock through 180° before bending it into U-shape, and the rib 26 of the previously-described embodiment is omitted. The twisting takes the form of two 90° twists, one at each extremity of the U-shaped portion 30, the respective 90° twists being made in the same sense or in opposite senses, as preferred. The mode of application of the anchor, and its stated advantages, are unchanged.

The rail anchor 31 illustrated in Figures 10 and 11 is formed from a length of flat stock, the rectangular section of which has not been altered in bending the same into a substantial U-shape as previously described. In this case the strength and section modulus of the intermediate portion are improved by welding to the exterior surface thereof a U-shaped supplemental strip 32, for example of rectangular section narrower than that of the anchor proper.

In that form of the invention illustrated in Figures 12 and 13, the anchor 31, similar to that of Figure 10, is supplemented by springing thereonto a U-shaped clip 33, for example of rectangular section somewhat wider than that of the anchor proper, the edges 34 being turned inwardly to prevent accidental lateral displacement of the clip.

In the embodiment illustrated in Figures 14 and 15, a strip of rectangular section is deformed, before bending, to provide outwardly directed lateral flanges 35. In the form illustrated in Figures 16 and 17 the strip material is deformed, before bending, to provide two spaced ribs 36 extending throughout the intermediate portion of the anchor. In each of the latter two embodiments, the cross-section of the anchor is narrowed somewhat, throughout the intermediate portion, in the course of the aforesaid deformation.

In the embodiment of Figure 16 it will be seen that the extremity 37 of the lower portion 38 of the anchor is bulged outwardly in its center portion to form a protuberance 39, seen in plan in Figure 18. This protuberance greatly facilitates the ease of removal of the anchor from a rail, since the extremity gripping the edge of the rail base may be much more easily struck with a maul or similar implement by virtue of the protuberance, thus minimizing the danger of striking the rail base, which might cause injury thereto.

The embodiment illustrated in Figures 19 and 20 is similar to that illustrated in Figures 1 and 5, except that the rib 40, unlike the rib 26, is extended to the end of the upper portion 41 of the anchor, thus providing a central longitudinally extending relief. Thus the upper portion 41 grips the rail base along two edge areas 42 and 43, and the unit pressure exerted by the anchor on the rail base is enhanced, thereby increasing the grip of the anchor upon the rail. This feature is of particular advantage if the rail base is covered with grease or dirt, and also prevents seating of the upper portion of the anchor along its central area only, through manufacturing inaccuracies, which would be disadvantageous.

The features just described may be carried forward by the employment, in the manufacture of rail anchors according to the invention, of strip material of other than flat rectangular section. For example, Figures 21 to 26, inclusive, illustrate a form of anchor employing strip material of angle section as the starting material. The material is deformed, before bending into U-shape so that the upper portion 45 and the lower portion 46 of the anchor 44 are approximately of the transverse section illustrated in Figure 26, while the intermediate U-shaped portion 47 has approximately the appearance, in transverse section, illustrated in Figure 25. The section modulus of the intermediate portion is thus of greater value than that of the upper and lower portions while,

at the same time, it will be apparent that the grip of the anchor upon the rail, by both the upper and lower portions, is exerted along marginal areas, as exemplified at 48 in Figure 26, the central areas between the respective marginal areas 48 being spaced from the adjacent surface of the rail base.

A protuberance 49 for facilitating removal of the anchor from a rail may, in the present embodiment, be conveniently formed as illustrated in Figures 21 and 24, 10 by slitting the distal end of the lower portion 46 into three segments and bending upwardly the extremities 50 of the outer segments while allowing the central segment to remain in alignment with the body of the lower portion 46. Alternatively, the entire distal extremity of the lower

15 portion 46 may be bent upwardly as seen in Figures 27-29, the protuberance 51 being constituted by the angular junction between the webs of the starter material while the marginal portions of the respective webs grip the edge of the rail base as illustrated.

20 It is contemplated, of course, that various combinations of the features illustrated and described herein, in a single anchor, may be advantageously employed.

Having thus described the invention, what is claimed as new and desired to be secured by Letters Patent is:

25 1. A rail anchor for use in securing a rail, having integral tapered base and web portions and fillets at the junction of said base and web portions, against longitudinal movement relative to the tie plate on which said rail is seated and the tie to which said tie plate is secured, comprising a spring steel member having a lower portion 30 adapted to extend across the bottom of the rail base in a direction normal to the length of the rail and having an upturned portion at one extremity adapted to engage an edge of said rail base, an upper portion extending at a 35 vertical angle to said lower portion and adapted to rest upon the upper face of said rail base on one side of the rail web and having an upturned extremity the lower surface of which is curved to match one of said fillets, and a generally U-shaped intermediate portion joining said lower and upper portions, at least the central part of said intermediate portion being of a cross-section the dimension of which, in a direction perpendicular to the plane of the edge of the rail base, is greater than the respective dimensions of the cross-sections of said lower and 40 upper portions in directions perpendicular to the rail surfaces with which these upper and lower portions are respectively adapted to contact.

2. A rail anchor for use in securing a rail, having integral tapered base and web portions and fillets at the 45 junction of said base and web portions, against longitudinal movement relative to the tie plate on which said rail is seated and the tie to which said tie plate is secured, comprising a spring steel member having a lower portion

50 adapted to extend across the bottom of the rail base in a direction normal to the length of the rail and having an upturned portion at one extremity adapted to engage an edge of said rail base, an upper portion extending at a 55 vertical angle to said lower portion and adapted to rest upon the upper face of said rail base on one side of the rail web and having an upturned extremity the lower surface of which is curved to match one of said fillets, and a generally U-shaped intermediate portion joining said lower and upper portions, at least the central part of said intermediate portion being of a cross-section the dimension of which, in a direction perpendicular to the plane

60 of the edge of the rail base, is greater than the respective dimensions of the cross-sections of said lower and upper portions in directions perpendicular to the rail surfaces with which these upper and lower portions are 65 respectively adapted to contact, said intermediate portion comprising a supplemental strip of metal secured to and along the U-shaped portion of said member.

70 3. A rail anchor according to claim 1, the section of said central part being derived from the original section of said member by deformation of said central part.

4. A rail anchor according to claim 1, the section of said central part being derived from the original section of said member by deformation of said central part to increase its dimension transverse to the longitudinal rail axis and decrease its dimension parallel to the said rail axis.

5. A rail anchor according to claim 1, the section of said central part being derived from the original section of said member by deformation of said central part to form at least one longitudinal element projecting outwardly beyond the plane of the remainder of said central part.

6. A rail anchor according to claim 1, the section of said central part being derived from the original section of said member by deformation of said central part to form at least one rib bulging outwardly beyond the general plane of said central part.

7. A rail anchor according to claim 1, the section of said central part being derived from the original section of said member by deformation of said central part to form at least one flange projecting outwardly beyond the general plane of said central part.

8. A rail anchor according to claim 1, said extremity of said lower portion being formed to provide a protuberance presenting a generally horizontal surface extending in a direction away from the rail axis to a point beyond said rail base edge engaging portion.

9. A rail anchor according to claim 1, the lower surface of said upper portion being formed to provide a central longitudinal element displaced upwardly from the general plane of said lower surface.

10. A rail anchor as defined in claim 1, the vertical angle between said lower and upper portions being less than the angle of taper of said rail base.

11. A rail anchor according to claim 2, said supplemental strip being welded to said member.

12. A rail anchor according to claim 2, said supplemental strip being detachably retained on said metal member by spring action.

13. A spring steel rail anchor for use in securing a rail, having integral tapered base and web portions and fillets at the junction of said base and web portions, against longitudinal movement relative to the tie plate on which said rail is seated and the tie to which said tie plate is secured, comprising a lower portion adapted to extend across the bottom of the rail base in a direction normal to the length of the rail and having an upturned extremity adapted to bear against an edge of said rail base, an upper portion extending at a vertical angle to said lower portion and adapted to rest upon the upper face of said rail base on one side of the rail web and having an upturned extremity the lower surface of which is curved to match one of said fillets, said lower and upper portions being of substantially rectangular cross-section, and a generally U-shaped intermediate portion joining said lower and upper portions, said intermediate portion being of a progressively varying section derived from a substantially rectangular section by deformation thereof to progressively increase the dimension thereof in a direction transverse to the longitudinal rail axis and progressively decrease the overall dimension thereof in a direction parallel to the said rail axis, said variation commencing at the respective ends of said intermediate portion, at the points where said intermediate portion merges with said upper and lower portions, and increasing to the midpoint of said intermediate portion, adjacent the deepest part of the U-bend thereof.

14. A rail anchor for use in securing a rail, having integral tapered base and web portions and fillets at the junction of said base and web portions, against longitudinal movement relative to the tie plate on which said rail is seated and the tie to which said tie plate is secured, comprising a lower portion adapted to extend across the bottom of the rail base in a direction normal to the length of the rail and having an upturned extremity adapted to

bear against an edge of said rail base, an upper portion extending at a vertical angle to said lower portion and adapted to rest upon the upper face of said rail base on one side of the rail web and having an upturned extremity the lower surface of which is curved to match one of said fillets, said lower and upper portions being of substantially rectangular cross-section, and a generally U-shaped intermediate portion joining said lower and upper portions, said intermediate portion being formed to provide an outwardly bulging lengthwise rib gradually increasing in height from its respective ends, at the points where said intermediate portion merges with said lower and upper portions, respectively, to its midpoint adjacent the deepest part of the U-bend of said intermediate portion.

15. A rail anchor as defined in claim 14, the over-all width of said intermediate portion decreasing as the height of said rib increases.

16. A rail anchor for use in securing a rail, having integral tapered base and web portions and fillets at the junction of said base and web portions, against longitudinal movement relative to the tie plate on which said rail is seated and the tie to which said tie plate is secured, comprising a U-shaped spring steel member having a lower portion adapted to extend across the bottom of the rail base in a direction normal to the length of the rail and having an upturned portion at one extremity adapted to engage an edge of said rail base, an upper portion extending at a vertical angle to said lower portion and adapted to rest upon the upper face of said rail base on one side of the rail web and having an upturned extremity the lower surface of which is curved to match one of said fillets, and a generally U-shaped intermediate portion joining said lower and upper portions, at least the central part of said intermediate portion being of a cross-section the dimension of which, in a direction perpendicular to the plane of the edge of the rail base, is greater than the respective dimensions of the cross-sections of said lower and upper portions in directions perpendicular to the rail surfaces with which these upper and lower portions are respectively adapted to contact, said member having a longitudinal rib extending throughout the length of the outer surface thereof, said rib being of greater height through said intermediate portion than in said upper and lower portions.

17. A rail anchor according to claim 16, said member comprising a length of angle stock the respective webs of which are deformed in portions adjacent the respective ends of said length to bring the distal margins of said webs into a common plane.

18. A rail anchor according to claim 16, said extremity of said lower portion being formed to provide a protuberance presenting a generally horizontal surface extending in a direction away from the rail axis to a point beyond said rail base edge engaging portion.

19. A rail anchor according to claim 17, said extremity of said lower portion being formed to provide a protuberance presenting a generally horizontal surface extending in a direction away from the rail axis to a point beyond said rail base edge engaging portion.

20. A rail anchor according to claim 17, said extremity of said lower portion being formed to provide a protuberance presenting a generally horizontal surface extending in a direction away from the rail axis to a point beyond said rail base edge engaging portion, a central part of said extremity extending in alignment with the main body of said lower portion to form said protuberance and the lateral parts corresponding to said central part forming the said upturned portion.

21. A rail anchor according to claim 17, said extremity of said lower portion being formed to provide a protuberance presenting a generally horizontal surface extending in a direction away from the rail axis to a point beyond said rail base edge engaging portion, a central part of said extremity extending in alignment with the

main body of said lower portion to form said protuberance and the lateral parts corresponding to said central part forming the said upturned portion, said central and lateral parts being separated from each other and integral with said main body.

22. A rail anchor for use in securing a rail, having integral tapered base and web portions and fillets at the junction of said base and web portions, against longitudinal movement relative to the tie plate on which said rail is seated and the tie to which said tie plate is secured, comprising a spring steel member having a lower portion adapted to extend across the bottom of the rail base in a direction normal to the length of the rail and having an upturned portion at one extremity adapted to engage an edge of said rail base, an upper portion extending at a vertical angle to said lower portion and adapted to rest upon the upper face of said rail base on one side of the rail web and having an upturned extremity the lower surface of which is curved to match one of said fillets, said lower and upper portions being of substantially rectangular cross-section, and a generally U-shaped intermediate portion joining said lower and upper portions, said inter-

5

mediate portion comprising a portion of material of substantially rectangular section twisted so that the greater dimension of the section extends in a plane normal to the rail axis.
